UNITED STATES PATENT OFFICE

CHARLES J. FUNK, OF CHICAGO, ILLINOIS, ASSIGNOR, BY DIRECT AND MESNE ASSIGNMENTS, TO PERIMO PRODUCTS CORPORATION, OF CHICAGO, ILLINOIS, A CORPORATION OF ILLINOIS

NEEDLE

Application filed October 12, 1929. Serial No. 399,306.

The invention relates to improvements in needles, and particularly to an improved needle adapted for use with sound reproducing or recording instruments.

5 An object of the invention is to provide an improved needle of the character referred to having the body formed of ordinary metal or metal alloy, such as steel, nickel, or copper and a nib or point of hard material such as, 10 for example, osmium, or a composition consisting of tungsten, carbon, and cobalt, known to the trade and referred to hereinafter as "carboloy", whereby material wear on the needle is practically eliminated, and the volume of sound reproduced or recorded thereby 15 remains substantially constant.

Another object of the invention is to provide an improved needle having a hard record-engaging portion, which is non-susceptible to rust; corrosion, or misshaping during continued use.

20 Another object of the invention resides in the provision of an improved needle having a very hard carboloy record-engaging portion shaped to remain in proper adjustment and outlast numerous phonograph records 25 or the like.

Another object of the invention is to provide an improved needle of the character 30 referred to having a carboloy record-engaging portion ground to the requisite degree of fineness, whereby the volume of sound reproduced or recorded thereby may be properly controlled.

35 Another object of the invention is to provide an improved needle having a carboloy record-engaging portion which can be inexpensively manufactured.

40 Needles adapted for use with sound reproducing or recording instruments of the various types formed of a single metal, usually require replacement after a short period of usage due to the wearing down or misshaping 45 of the cutting edge or record-engaging portion. When such wearing down or misshaping occurs the reproducing or recording records are frequently injured and the volume of sound recorded or reproduced varies or becomes distorted.

50 The improved needle, of the character

hereinbefore referred to, is such that it may be satisfactorily employed indefinitely without requiring replacement, readjustment, or cleaning, as the metallic alloy forming the cutting edge or record-engaging portion is 55 one of the hardest of known metals and resists wear to the extent that it outlasts the usefulness of numerous phonograph records. When polished and properly ground to the desired shape it resists corrosion and rust and 60 need not be readjusted or reground.

The material forming the record-engaging portion or cutting edge of the improved needle may be formed or ground to any desired shape or size according to the volume 65 of sound it is desired to reproduce or record therewith. The particular metallic elements forming the improved needle, as disclosed hereinbefore, afford means for accomplishing the foregoing and such other important 70 objects and advantages as will appear hereinafter as the description proceeds, and which will be more readily understood from a perusal of the following specification, reference being had to the accompanying drawing, in which:

Fig. 1 is an elevational view of one type of the improved needle.

Fig. 2 is a similar view of a ball point 80 needle embodying the invention.

Fig. 3 is a side elevational view of an arrow-head needle.

Fig. 4 is a fragmentary side elevational view of the needle shown in Fig. 3.

Fig. 5 is a perspective view of a modified 85 form of needle.

Fig. 6 is a perspective view, partially in section, of a cutting needle embodying the invention.

Fig. 7 and 8 are side and front elevational 90 views respectively of a modified form of cutting needle.

Referring to the drawing in detail, the improved reproducing needle 11, shown in Fig. 1, preferably comprises a body portion 12 95 having a tapered end 13. A record-engaging portion 14, formed of the hard metal, is ground or formed to the desired shape and welded, braised, or otherwise secured to the tapered end 13 and polished. The preferred 100

metallic substance forming the record-engaging portion 14 is as aforementioned that metal known to the trade as carboloy, composed of equal parts of tungsten, carbide, and cobalt. 5 These three substances are combined and molded or ground to the desired shape, as in this particular instance substantially frustroconical, and preferably secured to the body 12 by electro-welding or fusing.

10 The reproducing needle illustrated in Fig. 2, is similar in all respects to that shown in Fig. 1, except that a ball point record-engaging portion 15 is used to provide a coarse needle capable of reproducing a large tone 15 volume.

Figs. 3 and 4 illustrate another type of reproducing needle, particularly adapted for use on phonograph records, the body portion 16 of which is formed with the substantially 20 arrow-shaped end 17. This arrow-shaped end 17 preferably is tapered inwardly on all sides and a record-engaging portion 18 of hard material is braised or welded on its end. The hard record-engaging portion 18 is 25 preferably formed with a curved knife edge 18b adapted to align in the groove of the record.

In the form shown in Fig. 5 the body 19 of the needle is formed of flat stock having its end tapering to a curved knife edged record-engaging portion 18a of hard material, which 30 is substantially similar to the record-engaging portion 18.

Carboloy may also be satisfactorily employed for providing a cutting end on recording needles. As shown in Fig. 6, the body 21 of a needle of the known type is provided with a carboloy end 22 having an annular cutting edge 23 formed thereon by recessing the end, as at 24. Some other known types 40 of recording needles have a point or cutting edge formed of a metallic or mineral substance harder than that forming the body portion, but many of these materials injure the record or lack the hardness required to provide a needle which will remain serviceable indefinitely.

Figs. 7 and 8 show a modified form of cutting needle having a carboloy point 25 moulded or ground to form a substantially diamond or triangular shape providing a cutting point 26.

In operation, any one of the needles described in the foregoing is applied to the 55 usual recorder or reproducer instrument, in the usual manner, and it need not be replaced, cleaned, or readjusted at any time for the carboloy record-engaging portion retains its proper shape and position relative to the 60 groove indefinitely. The improved record-engaging portion does not scratch or cause undue wearing of the record. The carboloy record-engaging portion is practically indestructible, having a hardness of approximate- 65 ly 9.9, the hardest of known metals. This

mineral also resists corrosion and does not tarnish.

Although exemplary forms of the improved needle have been illustrated in the accompanying drawing and described in detail in the foregoing specification, it is not 70 desirous to have the invention limited to the precise materials or details of structure shown or described but only by such limitations as fall within the spirit of the invention, 75 and the scope of the appended claims.

I claim:

1. A needle, for reproducing sound comprising, in combination, a substantially round body, a portion of said body adjacent one end being substantially flat, the sides and edges of said flat portion tapering towards one end, and a wear-resisting record-engaging portion of harder material than said body on said tapered end formed with a curved 80 knife-like edge.

2. A needle, for reproducing sound, comprising, in combination, a body, a portion of said body adjacent one end being substantially flat, said flat portion being formed with tapering edges, and a wear-resisting record-engaging portion on said flat portion of harder material than said body formed with a curved knife-like edge. 90

3. A needle, for reproducing sound from a sound record having a groove therein, comprising, in combination, a body, a substantially flat portion adjacent one end of said body, said flat portion tapering on all sides 100 towards the same end, and a record-engaging portion of harder material than said body on said tapered end, said record-engaging portion being tapered to provide a curved knife-like edge.

4. A needle, for reproducing sound from a sound record having a groove therein, comprising, in combination, a body, a substantially flat portion adjacent one end of said body, said flat portion tapering on all sides 105 towards said end, a record-engaging portion of harder material than said body on said tapered end, and a substantially knife-like curved edge on said record-engaging portion arranged to co-operate with the record 110 groove. 115

In testimony whereof I affix my signature at Chicago, Illinois.

CHARLES J. FUNK.
